J. S. McWHIRTER,
SLOT CLEANER FOR STREET RAILWAYS.
APPLICATION FILED APR. 2, 1920.

Samuel S. Darby
his ATTORNEY

UNITED STATES PATENT OFFICE.

JOHN S. McWHIRTER, OF NEW YORK, N. Y.

SLOT CLEANER FOR STREET RAILWAYS.

Application filed April 2, 1920. Serial No. 370,744.

To all whom it may concern:

Be it known that I, JOHN S. McWHIRTER, a citizen of the United States, residing at New York, county and State of New York, have made a certain new and useful Invention in Slot Cleaners for Street Railways, of which the following is a specification.

This invention relates to means for cleaning dirt, snow, and the like, from the underground conduit employed in connection with electric railways such as street car systems in large cities where the electric current is supplied to the motors of the car from conductors located beneath the ground surface.

The object of the invention is to provide a cleaner which is simple in structure, efficient in operation, and which may be readily attached and detached.

A further object of the invention is to provide a cleaner which may be readily employed in connection with the passenger car.

Further objects of the invention will appear more fully hereinafter.

The invention consists substantially in the construction, combination, location, and relative arrangement of parts, all as will be more fully hereinafter set forth, as shown by the accompanying drawing, and finally pointed out in the appended claims.

Referring to the drawing:—

Fig. 1 is a view in front elevation, parts in section, of a car truck, and the underground conduit.

Fig. 2 is a detail view in section of a cleaner construction embodying my invention.

Fig. 3 is a sectional view taken on the line 3—3, Fig. 2, looking in the direction of the arrows.

The same part is designated by the same reference character wherever it occurs throughout the several views.

In the slot system of electrically operated street cars, that is, where the power is supplied to the motor of the car from a suitable conductor located beneath the ground surface and current therefrom supplied to the car motor through a contacting shoe carried by the car and extending through a slot in the ground surface, considerable dif-

ficulty is encountered in keeping the underground conduit clear of snow, ice, dirt, etc. This is especially true in snow storms where the snow readily sifts through the slot on unused portions of the track and becomes caked thereon. It has been the custom for many years to provide an especially equipped car or snow plow, which in addition to sweeping the surface of the tracks has been provided with a downwardly projecting arm of exceptional strong rigid character which extends through the slot and is provided with a rigid fan-shaped head extending transversely across the conduit and beneath the power conductor rails so that when the car is moved forwardly the fan-shaped head of this arm forces the snow, dirt, or the like, through the conduit in advance of the snow plow until the snow, dirt, etc., thus forced forwardly reaches a manhole in the conduit into which it is pushed by the forward movement of the car and thus discharged to the sewer system. In a severe snow storm however, especially where the number of specially equipped plows is small as compared to the total mileage of the system, and especially where the snow fall is a comparatively heavy one, the snow becomes caked so that when the snow plow and its slot arm moves forwardly the snow cakes into a solid mass and prevents the forward progression of the snow plow, thereby effectively stalling the plow and the entire system at that point. It is among the special purposes of my present invention to provide a cleaner device which will obviate this difficulty, and which will permit the cleaning device to be provided for each car, with facilities for ready attachment of the cleaning device to each car in the event of a storm to thereby prevent the snow from collecting in such an amount as to cause caking. In other words, in accordance with my invention I propose to provide a cleaning device which may be readily applied to each passenger car to thereby keep the conduits clean rather than allowing the snow, dirt, and the like, to collect, and only be cleaned out at the intermittent periods of operation of the specially constructed powerful snow plow.

Referring to the drawing, I show in Fig. 1 a portion of a slot railway system, comprising the rail 1 located on the ground surface 2, and supported in the usual manner by the block 3 and support 4. The conduit is shown at 5 in which are located the power rails 6. In the center of the track the Z-members 7 form between them the usual slot 8, the Z-members supporting the plates 9 and being connected to the rail 1 through the tie rods and beams 11 and 10 respectively to thereby form a rigid structure. A portion of a car truck is shown comprising the wheel 13 and journal 14 and a portion 15 of the bolster 15. The bolster 15 is provided with a rectangularly shaped arm 16 which extends through the slot 8 and carries thereon the compressible shoes 17, which contact with the rails 6 to thereby form a complete 20 input and output circuit for the current which is fed up through the arm 16 to the car motor in the usual well known manner.

It will be understood that throughout a railway system of this nature at intervals a 25 manhole is provided at the bottom of the conduit 5, and also that the Z-beams 7 at intervals are so formed as to permit the rocking thereof to permit the widening of the slot 8. As a matter of fact at intervals 30 throughout the railway system of this nature means are provided to permit a workman to enter the conduit for various purposes of repair, etc. In accordance with my invention I propose to extend the arm 16 to 35 a point below the rails 6 and to secure thereto in any suitable manner, for example, by means of brackets 20, a cleaning device, for example, the brush 21, the head of which is of a non-conducting material, 40 such as wood, and which comprises a series of stiff bristles 22 of wire, or the like, which, although quite stiff, possesses a certain amount of resiliency. With the arrangement above described it will be apparent 45 that a brush of this nature may be employed on every contacting slot arm of each passenger car, either at all times when the car is in continual operation, or may be carried by the car and attached to the arm only in 50 the event of a snowstorm, or the like, thereby effecting a cleaning of the conduit while the car is being propelled and thus obviating the necessity of a special car or snowplow to clean the conduit, and at the same 55 time, due to the more frequent operation of the passenger cars than snowplows, tending greatly to diminish the possibilities of an accumulation of snow, dirt, or the like, to such a stage where the snowplow would be 60 ineffective in cleaning the conduit and only effective in completely blocking the same. Even in case of a blocking of a certain amount of snow or refuse material within the conduit it would not be necessary for

the car to become stalled inasmuch as the resiliency of the brush bristles would be sufficient to permit the brush to pass over any particular accumulation or cake of the snow or refuse material in case of necessity.

If it is desired the equipment may be carried by the car or may be stored in manholes along the line provided for that purpose. Further, the structure may consist of an auxiliary arm 26, similarly shaped rectangularly, and provided at its top end with a cross head 27 and at its bottom end with the brush 21. In this arrangement the bolster 15 would be formed with channel members 28 so that in case of a snow storm the Z-members 7 at any point provided therefor in the system could be rocked to widen the slot 8 to at least the transverse width of the arm 26 so that the longitudinal axis of the brush 21 would coincide with the longitudinal axis of the slot and thereby pass freely between power rails 6 when the same is inserted in the slot and also so that the cross head 27 would lie in a longitudinal axis parallel to the channel members 28. The arm 26 is then rotated through 90 degrees so that the brush 21 extends transversely across the bottom of the conduit 5, and the ends of the cross head 27 will be located in the channel portions 28 of the bolster 15. The Z-members 7 are 95 then closed to their normal position to form the normal slot 8 and locked in the usual manner, and the car is ready to continue its travel. To avoid forming a contact between the arm 26 and the end of the rails 6, due to oscillatory movement of the arm 26, I provide a suitable collar 30 of non-insulating material, preferably of wood, for the portion of the arm 26 which when positioned is 100 opposite the rail 6.

Many other modifications and changes in detail will readily occur to those skilled in the art without departing from the spirit and scope of my invention as defined in the claims, but having shown and described one 110 construction embodying my invention, what I claim as new and useful and of my own invention and desire to secure by Letters Patent is,—

1. In an underground conduit and slot system for electric street railways, and in combination with a truck unit, of an arm adapted to extend through said slot into said conduit and provided with a cleaning member at the end thereof, and a cross-head 115 for securing said arm to the truck unit to permit the ready attachment or detachment thereof.

2. In an underground conduit and slot system for electric street railways, and in combination with a truck unit, of an arm adapted to extend through said slot into said 120 conduit and provided with a resilient clean-

ing member at the end thereof and a cross-head at the other, and means for engaging said cross-head to secure the same to the truck unit for permitting ready attachment 5 or detachment thereof.

3. In an underground conduit and slot system for electric street railways, and in combination with a truck unit, of an arm adapted to extend through said slot into said

conduit and provided with a bristle brush 10 at the end thereof and a cross-head at the other, and channel members for securing said cross-head to the truck unit.

In testimony whereof I have hereunto set my hand on this 24th day of March, A. D., 15 1920.

JOHN S. McWHIRTER.
